ROAD SPREADER

Clyde G. Abernathy, Hornell, N. Y.

Application February 17, 1932, Serial No. 593,495

26 Claims. (Cl. 94—44)

This invention relates to a road spreader and more particularly to a machine for laying and grading stone and asphalt mixes upon roadways in resurfacing the same or in providing an original surface or base for the road. The machine is more particularly intended for use in laying and grading cold mixes of stone, asphalt and a solvent for the asphalt but can also be used with hot mixes.

10 In laying and grading surfacing of asphalt and stone considerable difficulty has been encountered by reason of the fact that the stone and asphalt mix is extremely heavy and difficult to handle. Particular difficulty has been encountered in attempting to lay and grade such mixes mechanically by means of road machinery. It is therefore the principal object of this invention to provide a machine which lays and grades heavy mixes of asphalt and stone, or the like; 15 which will handle large quantities of such mixes and accurately grade the same to provide the smooth and uniform surface desired; and which accomplishes this without requiring any handling of the mix, the mix being dumped directly 20 into the hopper of the machine from the trucks for transporting the mix to the job.

Another object is to provide such a machine in which the hopper is provided with a toothed rotating raker which not only agitates the material 30 in the hopper so as to break it up and thereby provide a uniform dispersion of the material over the full width of the hopper but also cuts below the lever of the surface of the road being laid so as to insure the uniform deposit of the 35 material from the hopper onto the road and insure an accurate and smooth surface. In the preferred embodiment the teeth of this raker are made removable and are also arranged spirally so that when a truckload of material is dumped 40 into the hopper the blades tend to spread it out the full width of the hopper and insure the uniform deposit of it over the full width of the strip of road being laid.

Another object is to so design the hopper that the weight of great masses of material in the 45 hopper is prevented from bearing directly on this rotating raker thereby insuring that it operates at full efficiency and without undue loads or strains.

Another purpose is to provide a toothed strike-off member which is reciprocated transversely of the machine and is arranged immediately in rear of the rotating raker which projects below 50 the lower open end of the hopper. This strike-

off member determines the final surface of the road and is so formed that it provides a smooth and uniform surface. In its preferred form the teeth of this strike-off member are removable and are also beveled on their underside so that a crowding action takes place, the bevel crowding down upon the material and compressing it so that the surface of the road is smoothed.

A further object is to so mount this strike-off member that it can be easily adjusted vertically thereby permitting the machine to be used in laying the materials in layers of different thicknesses as different specifications may demand. In providing this mounting provision is also made for transmitting the reciprocating motion 10 to the strike-off member in all of its elevated positions which means are simple and reliable and arranged in such manner that they will not become coated with the asphalt.

A further purpose of the present invention is 20 to provide a machine of this character which by very simple alterations is adapted to be used either with or without forms, such forms consisting in rails arranged along the side of the road and on which the machine travels. When used 25 in either manner the machine is readily steered.

Another object is to provide a machine in which the rear wheels act as a roller and run on the surface of the road already laid. This not only 30 serves to roll the laid surface of the roadway and provide a better surface but also, when forms are used, takes a part of the weight of the machine off of the form. These rear wheels are also so disposed that they are arranged close to the form boards or rails and thereby roll the 35 road at a place that could not be rolled by a steam roller and formerly required hand tamping. The rear wheels are also preferably beveled slightly so as to prevent the steam rollers from breaking down the edge of the road during the 40 subsequent rolling of the roadway laid by the present machine.

A further object of the present invention is to provide a machine which is adapted for use both in fine grading with gravel as well as the grading 45 of coarser materials. For this purpose the rotating raker is lifted and the reciprocating strike-off member is dropped.

Another object is to provide a machine which is entirely self-contained and the same prime 50 mover is used to propel the machine and also to rotate the raker and reciprocate the strike-off member. Another object is to render the machine easily adjustable throughout and capable of easy operation. Another purpose is to provide 55

a machine which is exceedingly simple and strong in construction and reliable in its operation and will stand up under conditions of severe and constant use without getting out of order.

- 5 In the accompanying drawings:

Fig. 1 is a side elevation of a road spreader made in accordance with my invention and showing the same used in connection with forms or rails at the side of the strip of road being laid.

- 10 In this figure is also shown, in dotted lines, the bars which are used for supporting the strike-off member when the machine is used without forms or side rails.

- 15 Fig. 2 is a top plan view of the machine shown in Fig. 1 also showing in dotted lines the bars for supporting the strike-off member when forms are not used.

Fig. 3 is a longitudinal central section through the road spreader shown in Figs. 1 and 2.

- 20 Fig. 4 is a transverse section taken on line 4—4, Fig. 3.

Fig. 10 is a horizontal section taken on line 10—10, Fig. 9.

- 40 Fig. 11 is a fragmentary side elevation similar to Fig. 1 showing a modified form of the invention in which a caterpillar tread is employed instead of the rollers shown in Fig. 1.

- Fig. 12 is a fragmentary view similar to Fig. 4 and showing a modified form of strike-off bar which is designed to provide a rounding crown on the road bed and is also so designed that this crown can be adjusted to meet different specifications.

- 50 Fig. 13 is a vertical section taken on line 13—13, Fig. 12.

Fig. 14 is a perspective view of one of the teeth 68 of the rotary raker.

- 55 Similar characters of reference indicate like parts in the several figures of the drawings.

In its general organization this invention consists in a frame which is so supported that it can be propelled along the ground on which a strip of rock and asphalt is to be laid and which 60 is provided with a hopper into which the material can be dumped directly from a truck. The bottom of this hopper is open and projecting through this opening is a rotary raker which breaks up the material deposited into the hopper 65 and also cuts down below the level of the road to be laid so that a compact and uniform layer of the material is deposited on the road. Immediately in rear of this rotary raker is a reciprocating strike-off member which grades the surface 70 face of the road to the desired thickness and also smooths off and compresses this surface so that the material deposited is in shape for rolling after the machine has laid the strip. The machine is run by a prime mover preferably in the 75 form of a gasoline motor and the various parts

are adjustable throughout so that it can be used to lay a wide variety of road making material and also can be used to pay them in the thickness required in the road specifications.

As previously stated the machine is adapted to 5 be used either with or without forms. These forms consist of rails 15 arranged at each side of the strip of material to be laid and suitably supported in any suitable manner. These forms are generally made of metal although any material 10 can be used. When used, the height of these forms determine the thickness of the layer of material to be laid and the material is laid flush with the upper edge of the forms.

The frame of the machine is shown as made 15 up of channel beams, two beams 16 being arranged at either side of the machine and these beams being connected by cross beams 17 arranged at suitable intervals as determined by the arrangement of the other parts of the machine as 20 hereinafter described. The rear end of the frame is in part supported by a pair of wheels 18 which, when the forms 15 are used, ride upon these forms. These wheels are therefore each arranged adjacent the rear end of the side beams 25 16 and are each carried by a bracket 19 which is secured to the rear end of the frame and is formed to provide rearwardly opening upper and lower jaws. As best shown in Fig. 9 each of the 30 wheels 18 is embraced by a yoke 20, the axle 21 for the wheel extending through the lower ends of the two arms of this yoke. The upper end of this yoke 20 is squared, as indicated at 22 and is mounted in a square hole in the lower jaw of the yoke 19. In the squared portion 22 of 35 the yoke is screwed a post 23 and this post is held against turning therein by a cross pin 24. This post extends through the upper jaw of the yoke 19 and at its upper end carries a hand wheel 25, the purpose of which is to adjust the spring pressure between the wheel 18 and the frame.

This spring pressure is provided by a spring 26 which is arranged between the two jaws of the yoke 19 and surrounds the corresponding part of the post 23. At its lower end this spring bears 45 against the squared portion 22 of the yoke which is connected with the wheel 18 and the upper end of this spring bears against a plate 27 which is in turn forced against the lower end of an externally threaded sleeve 28. This sleeve works in 50 a nut 29 which is carried by the upper jaw of the bracket 19 and secured in place by screws 30. The upper end of the threaded sleeve 28 is fixed to the hand wheel 25 and a collar 31 is provided to limit the upward movement of the threaded 55 sleeve 28 relative to the post 23. The downward movement of the parts is limited by a sleeve 32 which surrounds the post 23 and is interposed between the squared part 22 of the bracket 20 and the plate 27.

It is apparent that upon screwing down the hand wheel 25, the threaded sleeve 28 is turned so as to force the spring 26 down and exert more pressure upon the bracket 20 and the wheel 18. The screwing down of the hand wheel 25 thereby 60 serves to elevate the rear end of the frame and at the same time a spring suspension is provided for the rear end of the frame.

The front end of the frame is supported by two front wheels 35 which are arranged at the 70 front ends of the side beams 16 and preferably track inside of the forms 15. These wheels are arranged so that through them the machine is steered and consequently each is preferably supported as follows:

Each wheel 35 is provided with an axle 36 which connects with the depending arms of a yoke 37. This yoke is formed to provide an upright post or king pin 38 which is journaled in a bracket 39 in any suitable manner. This bracket 39 is connected with the front end of the corresponding side beams 16. To the yoke 37 is also secured a sector 40 which extends outwardly and meshes with a worm 41. Each of these worms 41 is fixed to a longitudinal shaft 42 which is suitably journaled on the main frame and carries a beveled pinion 43 at its rear end. These pinions 43 mesh with corresponding pinions 44 on a cross shaft 45, this cross shaft 45 being also journaled in brackets provided on the main frame and one of the pinions 44 also meshes with a pinion 46 at the lower end of an inclined steering post 47. This steering post can be journaled in any suitable manner and at its upper rear end carries a steering wheel 48 by means of which the steering post is turned to deflect the wheels 35 accordingly.

It is apparent that upon turning the steering wheel 48 the cross shaft 45 is turned and also each of the worm shafts 42 is turned to move the segments 40. This movement turns the wheels about the king pins 38 as an axis and consequently steers the machine.

In the center of the machine a hopper, indicated generally at 50, is arranged. This hopper is preferably made of sheet metal and consists of side plates 51, a lower plate 52 and a rear plate which is made of three plates 53, 54 and 55 disposed at an angle to one another. The bottom plate 52 is preferably arranged at a comparatively flat angle relative to the road, its lower end terminating adjacent the surface of the road to be laid and its upper end being sufficiently low so that trucks can conveniently drop the material to be laid directly into the hopper. Immediately in rear of this lower plate 52 the hopper is provided with a lower opening 56 and this opening is overhung by the plate 54 and the lower end of the plate 53 in such manner that the weight of the material in the hopper is in part borne by the rear wall of the hopper and the material is prevented from compacting in the form of a solid mass in the lower open part of the hopper.

The machine is propelled and its parts moved by a prime mover which is shown as consisting of a gasoline motor indicated generally at 60. The shaft 61 of this motor is arranged transversely of the machine and is connected by a change speed gear 62 with a shaft 63, this shaft 63 being suitably journaled in a bracket on one of the side beams 16. This shaft carries a sprocket 64 which is connected by a chain 65 with a sprocket 66. This sprocket is fixed to the corresponding end of a squared shaft 67 the opposite ends of which are journaled in vertically adjustable bearings, as hereinafter described. This shaft extends the complete width of the hopper and is disposed immediately above the opening 56 in its bottom. This squared shaft 67 carries a plurality of teeth 68 each of which is provided with a pair of arms 69, these arms embracing the squared shaft 67 and being held in tight engagement therewith by a bolt 70 which connects the arms 69 at the side of the shaft 67 opposite from the tooth 68. Each of these teeth is generally of scimitar form and the shaft is rotated in such manner that the indented side of each tooth digs downwardly into the material being laid and forces it rearwardly. These teeth 75 are sufficiently long so that they project below

the opening 56 in the hopper and below the level to which the road material is being laid so that these teeth cut into the road itself and insure a uniform distribution of the stone or other aggregate as well as serving to compact the road material as it is laid. The teeth 68 are preferably spirally disposed along and around the shaft 67 so that as a load of material is dropped into the hopper 50 the teeth of the rotary raker tend to spread it out uniformly along the full width of the hopper. It is also apparent that the overhanging form of the rear wall of the hopper tends to relieve this rotary raker of the full pressure of the load of material in the hopper and thereby permits it to be operated with less power and with greater effectiveness.

The motor shaft 61 also connects with another change speed gear 75 which drives a longitudinal shaft 76. On this shaft is fixed a sprocket 77 which is connected by a chain 78 with a sprocket 79 on a lower longitudinal shaft 80. This shaft 80 is suitably journaled in brackets on the main frame and at its front end carries a disk 81 provided with a crank pin 82. This crank pin 82 connects to a transverse connecting rod 83, the other end of which is connected to a pin 84 projecting rearwardly from a reciprocating angle bar 85. This bar 85 is mounted for reciprocatory movement transversely of the machine, as herein-after described and to its lower side are secured a plurality of plates 86 which are formed to provide forwardly extending teeth. These teeth are removably secured in any suitably manner as by a pair of small screws 87 and as best shown in Fig. 6 each of these plates is pointed at its front end. The underside of the front pointed end of each of these teeth 86 is also beveled as indicated at 88.

These teeth are disposed immediately below the rear end of the opening 56 in the hopper 50 and immediately in rear of the toothed rotary raker. The teeth therefore act as a strike-off member in leveling and surfacing the material being laid, the rotary raker forcing the material against the underside of these teeth and the beveled form of the teeth serving to force the material so fed to them downwardly. It is apparent that the strike-off member which is formed by the angle bar 85 and its teeth 86 is reciprocated through its connection by the link 85 with the crank pin 82 with the motor and the weight of the strike-off member upon its support and the weight of the material on the strike-off member is relieved by the rotary raker which lifts the material away from this strike-off member as it rotates. It is also apparent that the provision of bevels 88 on the teeth 86 also tends to lift the strike-off member and relieve its weight upon its supports.

Both the strike-off member and the rotary raker are made vertically adjustable so as to suit the particular material being laid and also to determine the thickness of the layer being laid. Thus when the material is coarse the rotary raker is depressed so that it cuts deeply below the surface of the layer being laid and secures a uniform distribution of the material. When, however, light gravel is being laid the rotary raker is elevated relative to the strike-off member so that the rotary raker serves primarily merely to distribute the material and the strike-off member effects the surfacing. Also when a relatively thin layer is being laid both the strike-off member and the rotary raker are, of course, elevated. When, also, a very thin layer of material is being laid it is apparent that the digging effect of the rotary raker

must be very slight since otherwise it would dig into the base as well as into the layer of material being deposited.

- For the purpose of rendering the rotary raker 5 shaft 67 vertically adjustable it is journaled at each end in a slide 90 which is arranged in slide-ways provided by guides 91, these guides being suitably secured to the side plates 51 of the hopper. The upper end of the slide 90 is formed to 10 provide an outwardly projecting flange 92 and to each of these flanges 92 is secured a post 93. This post 93 is rigidly connected to the flange 92 by a nut 94 which screws upon the reduced threaded end of the post 93, this reduced threaded 15 end extending through the flange 92. The upper end of this post 93 is threaded and on the upper threaded end of this post 93 is mounted a hand wheel 95, the hub of which is internally threaded to screw upon the threads of the post 93. This 20 hand wheel is held against vertical movement and for this purpose the upper end of the post 93 extends through a bracket 96 the upper end of which is provided with a recess 97 which receives the lower part of the hub of the hand wheel 95. 25 The hub of the hand wheel 95 is also provided with a groove 98 and in this groove are arranged a pair of plates 99 which are secured to the bracket 96 by screws or in any other suitable manner. It is apparent that the plates 99 prevent the hand 30 wheel 95 from moving vertically and consequently upon turning the hand wheels 95 at each side of the machine, the corresponding posts 93 are elevated to lift the slides 92 and raise the rotary raker shaft 67 which is carried thereby.
- 35 To provide for the vertical adjustment of the strike-off member the opposite ends of the angle bars 85 are each provided with an arm 100 which extends outwardly from the corresponding end of the angle bar 85 and is connected in any suitable manner to the lower end of a chain 101. The upper end of each of these chains is carried by a rock arm 102 both of these rock arms 102 being mounted on a cross shaft 103 which extends the full width of the machine and is suitably 40 journaled in brackets from the rear plate 53 of the hopper. This rock shaft 103 is turned by means of a lever 104. This lever traverses a stationary segment 105 having teeth 106 and the lever is provided with a releasable catch 107 by 45 means of which any of the teeth 106 in the segment 105 can be engaged and the lever 104 held in a corresponding position. It is apparent that when the lever 104 is held by the lower teeth of the segment 105, the angle bar 85 of the strike-off member will be held in an elevated position and that when the lever 104 is held in an elevated 50 position the strike-off member will be permitted to fall to a depressed position.

The strike-off member formed by the angle bar 60 85 and its teeth 86 is preferably provided with bearing plates 108 which permit the strike-off member to rest and slide freely upon the upper sides of the forms 15 when the forms are used. The strike-off member is also supported against 65 rearward movement by rollers 110. Two of such rollers 110 are provided and each is carried at the lower end of a bracket 111 which depends from the main frame and each roller engages a bearing plate 112 which is secured to the rear ends of the corresponding teeth 86. It is therefore apparent that 70 these rollers 110 take the rear thrust of the strike-off member and hold it in position.

The machine is also propelled by the gasolene motor 60. For this purpose the shaft 61 of the 75 motor is provided with a sprocket 115 which is

connected by a chain 116 with a sprocket 117, this sprocket 117 being fixed to a main cross shaft 118. This main cross shaft is journaled in bearings 119 on the main frame and immediately inside of the longitudinal beams 16 of the main frame carries a pair of driving rollers 120. These rollers therefore rest upon the surface of the strip of material laid by the machine and therefore serve not only to propel the machine but also serve to compress the strip of material laid immediately inside of the forms 15. These wheels therefore roll the roadway at a place that it is impossible to reach with the usual steam rollers since the use of steam rollers would break down the shoulders or corners at the sides of the strip. 15

When the machine is being used with the forms 15 the bearing plates 108 of the strike-off member can rest directly upon the forms 15. When, however, the machine is being used without the forms 15 it is necessary to provide a support for the 20 strike-off member which at the same time permits it to be adjusted vertically as previously described. When the machine is to be used without forms a pair of bars 125 are arranged at opposite sides of the machine and the front end of 25 each is pivotally connected to the frame of the machine. Each of these bars is bent so that its rear end is arranged under the arms 100 and the rear ends of these bars 125 are connected together by a cross rod 126. On this cross rod 126 is 30 mounted a pair of rollers 127 which are adapted to rest upon the surface of the strip laid by the machine. It is apparent that when the machine is being used without forms that the reciprocating strike-off member is supported directly by the 35 bars 125 and since these bars are supported at one end on the frame and at their other ends by the rollers 127 the strike-off member is supported in the same manner as if the forms 15 were used and the strike-off member supported thereby. It is 40 also apparent that since the front ends of the bars 125 are supported at the front end of the machine, any elevation or depression of the front end of the machine in passing over a rough base will 45 not materially affect the elevation of the strike-off member since the rollers 127 are arranged immediately in rear of the strike-off member.

In Fig. 11 is illustrated a modification of the present invention. Instead of providing the rollers 120 for driving the machine and also rolling the shoulders on the strip laid a caterpillar drive is provided. A caterpillar tread is provided at each side of the machine and is supported on the main shaft 118 of the machine. For this purpose the caterpillar drive includes a pair of side plates 55 130 which are carried by the main shaft 118 and at their ends carry sprockets 131 and 132 on which the caterpillar tread 133 rides. This caterpillar tread 133 also rides upon a sprocket (not shown) which is loosely mounted on the main 60 shaft 118. The sprocket 132 is mounted upon a shaft 134 which also carries a sprocket 135. This sprocket is connected by a chain 136 with a sprocket 137 this last sprocket 137 being fast to the drive shaft. The shaft 134 is preferably adjustable along the plates 130 so that any slack in the caterpillar tread on the drive chain 136 can be taken up. The main shaft is driven in the same manner as in the preferred construction and it is therefore apparent that the turning of the 70 main shaft drives the caterpillar tread through the train comprising the sprocket 137, chain 136, sprocket 135, shaft 134, sprocket 132 and caterpillar tread 133.

Where specifications require a transversely 75

crowned or rounded road bed a special form of 5
strike-off bar or member is provided which is de-
signed to provide this crown. This strike-off bar
is also adjustable so that crowns of different types
or degrees of curvature can be provided. This
modification of the invention is shown in Figs. 12
and 13 and comprises a channel bar 140 which is
arranged transversely of the machine and is
mounted on the longitudinal frame bars 15. This
channel can be secured in any other manner and
carries a plurality of depending bolts 141. The
heads of these bolts are at their lower ends and
nuts are provided at their upper ends above the
transverse channel bar 140. Secured to the lower
ends of these bolts in any suitable manner is a
flexible strip 142 which extends the full width
of the machine. It is therefore apparent that
upon adjusting the different bolts 140 the flexible
strip 142 can be adjusted to have any desired
20 curvature. Below the flexible strip 142 is another
flexible strip 143 which carries a plurality of up-
right brackets 144. These brackets are U-shaped
and embrace the front and rear sides of the flex-
ible strip 142 and each bracket 144 carries two
25 pairs of rollers 146. These rollers ride on the
upper and lower faces of the flexible strip 142, as
best shown in Fig. 13. It will be understood that
the space between the bolts 141 is sufficient to
allow the requisite amount of travel for the brack-
30 ets 144 and their rollers.

The strike-off teeth 86 are secured to the un-
derside of the flexible strip 143, these strike-off
teeth being of the same form as the strike-off
teeth 86 in the preferred construction. The flexi-
35 ble strip 143 is reciprocated in any suitable man-
ner as by the crank construction shown in Fig. 4,
and it is therefore apparent that the reciprocation
of this flexible strip 143 and its teeth 86 cause
them to follow the curvature imposed upon the
40 flexible strip 142 and therefore a corresponding
crown is provided on the roadway being surfaced.

From the foregoing it is apparent that the pres-
ent invention provides a very simple, efficient and
relatively inexpensive machine for surfacing roads
45 which will handle large quantities of material
and will stand up under conditions of severe and
constant service without getting out of order or
requiring repairs. The machine is also so de-
signed that it operates with a minimum of power
50 and will also insure a uniform texture to the ma-
terial being laid and also insure that it is laid to
a uniform depth. The machine also provides a
smooth and compact surface on the road and
leaves it in a condition for rolling. The machine
55 is also adjustable throughout so that it is adapt-
ed for laying a wide variety of road materials and
it is also adjustable to lay any desired thickness
of road materials. The machine is also adapted
for use without forms and is so designed that it
60 can be easily transported to and from the place
of operations with little difficulty.

I claim as my invention:

1. In a road spreader of the character described,
a carriage, a hopper mounted on said carriage
65 and having an elongated opening in its bottom,
said opening being arranged transverse of the line
of movement of said carriage, a strike-off mem-
ber arranged in rear and parallel with said open-
ing, said strike-off member being provided with
70 horizontal teeth which project forwardly under
said opening adapted to smooth out the material
being discharged through said opening and means
for reciprocating said strike-off member length-
wise of said opening.

2. In a road spreader of the character described,
a carriage, a hopper mounted on said carriage and

having an opening in its bottom, a strike-off mem-
ber arranged adjacent and in rear of said open-
ing and arranged to smooth out the material dis-
charged therethrough, horizontal teeth provided
at the advance edge of said strike-off member and
projecting forwardly under said opening to
smooth out the material being discharged through
said opening, said teeth being provided with an
undercut bevel to compact the material there-
under and means for reciprocating said strike-
off member transversely of the line of movement
of said carriage. 10

3. In a road spreader of the character de-
scribed, a carriage, a hopper mounted on said
carriage and having an opening in the bottom, 15
a bar arranged transversely of the line of move-
ment of said carriage, a plurality of forwardly
projecting teeth mounted on said bar, said teeth
being arranged under said opening to smooth
out the material being discharged therethrough 20
and means for reciprocating said bar longi-
tudinally.

4. In a road spreader of the character de-
scribed, a carriage, a hopper mounted on said
carriage and having an opening in its bottom, a 25
strike-off member arranged to project under said
opening to smooth out the material being dis-
charged therethrough, means for reciprocating
said strike-off member transversely of the line
of movement of said carriage and means for 30
adjustably varying the elevation of said strike-off
member.

5. In a road spreader of the character de-
scribed, a carriage, a hopper mounted on said
carriage and having an opening in its bottom, 35
a pair of flexible members depending from the
opposite sides of said carriage immediately ad-
jacent said opening, a strike-off member sup-
ported at its opposite ends by said flexible mem-
bers, said strike-off member being arranged un-
der said carriage and immediately adjacent said
40 opening to smooth out the material being dis-
charged therethrough, means for reciprocating
said strike-off member transversely of the line
of movement of said carriage and means for ad-
justing the effective length of said flexible mem-
bers to adjustably regulate the elevation of said
strike-off member. 45

6. In a road spreader of the character de-
scribed, a carriage, a hopper mounted on said 50
carriage and having an opening in its bottom, a
strike-off member projecting under said opening
to smooth out the material discharged there-
through, means carried by said carriage for ad-
justably regulating the elevation of said strike-
off member relative to said carriage and means
55 for reciprocating said strike-off member trans-
versely of the line of movement of said carriage
at all elevations comprising a crank journaled in
said carriage, a link connecting said crank and
strike-off member and means carried by said
carriage for turning said crank. 60

7. In a road spreader of the character de-
scribed, a carriage, a hopper mounted on said
carriage and having an opening in its bottom, 65
a strike-off member arranged under said opening
to smooth the material discharged therefrom,
means for moving said strike-off member and
means for supporting the load of material in said
hopper so that the full weight thereof is not borne
70 by said strike-off member.

8. In a road spreader of the character de-
scribed, a carriage, a hopper mounted on said
carriage and having an opening in its bottom,
a strike-off member arranged under said open- 75

- ing to smooth the material discharged therefrom, means for moving said strike-off member and means for supporting the load of material in said hopper so that the full weight thereof is not borne by said strike-off member comprising a projection provided in one wall of said hopper and overhanging said strike-off member. 5
9. In a road spreader of the character described, a carriage, a hopper mounted on said carriage and having an opening in its bottom, a rotary raker arranged in said hopper and having its axis arranged transverse of the line of movement of said carriage, said rotary raker being provided with teeth and said teeth projecting through said opening and below the level of the surface being laid and means for turning said raker. 10
10. In a road spreader of the character described, a carriage, a hopper mounted on said carriage and having an opening in its bottom, a rotary raker arranged in said hopper adjacent said opening and having its axis arranged transverse of the line of movement of said carriage, means for turning said rotary raker to control the discharge of the material through said opening and means for adjustably varying the elevation of said raker. 15
11. In a road spreader of the character described, a carriage, a hopper mounted on said carriage and having an opening in its bottom, a rotary raker arranged in said hopper adjacent said opening and having its axis arranged transverse of the line of movement of said carriage, means for turning said rotary raker to control the discharge of the material through said opening and means for adjustably varying the elevation of said raker comprising a vertically movable plate arranged at each side of said hopper, means for guiding said plate, a bearing provided in each plate and journalling the corresponding end of said raker and screw means interposed between each bearing plate and said carriage for raising and lowering said plate. 20
12. In a road spreader of the character described, a carriage, a hopper mounted on said carriage and having an elongated discharge opening arranged transverse of the line of movement of said carriage, a strike-off member arranged in rear and parallel with said opening and arranged to smooth off the material discharged through said opening, a rotary raker arranged in said hopper adjacent said opening, said rotary raker having its axis arranged parallel with said opening and having teeth adapted to project down through said opening and below said strike-off member and means for turning said raker in the direction in which it crowds the material discharged through said opening rearwardly and upwardly under said strike-off member. 25
13. In a road spreader of the character described, a carriage, a hopper mounted on said carriage and having a discharge opening in its bottom, a rotary raker mounted in said hopper adjacent said opening and controlling the discharge of material therethrough, means for rotating said raker and means for preventing the full weight of the material in said hopper from bearing on said raker, comprising a baffle in said hopper above said raker. 30
14. In a road spreader of the character described, a carriage, a hopper mounted on said carriage and having a discharge opening in its bottom, a strike-off member arranged adjacent said opening and arranged to smooth out the material discharged through said opening and to determine the thickness of the layer of roadway being laid, an auxiliary frame supporting said 35
- material discharged through said opening and to determine the thickness of the layer of roadway being laid, an auxiliary frame supporting said strike-off member, means pivoting said auxiliary frame to said carriage at the front ends thereof and a traction member supporting the rear end of said auxiliary frame and riding on the surface of the roadway already laid immediately in rear of said strike-off member. 40
15. In a road spreader of the character described, a frame, front traction members supporting said frame, a hopper arranged in the center of said frame and having an opening in its bottom, means for discharging and distributing the material from said hopper opening to lay a uniform layer of material on the roadway, a pair of traction members at the rear of said frame and resting on and compressing the roadway already laid and means for applying power to said rear traction members to propel said frame. 45
16. In a road spreader of the character described, a frame having a pair of front traction members and a pair of rear traction members, a hopper arranged in the center of said frame and having an opening in its bottom, means for discharging and distributing the material through said hopper opening to lay a uniform layer of material on the roadway, a pair of traction members connected to said frame in rear of said hopper and resting on and compressing the freshly laid roadway and means for applying power to one of said traction members to propel said frame. 50
17. In a road spreader of the character described, a frame, means for supporting the front and rear ends of said frame for movement along the surface to be paved, a hopper arranged in the center of said frame and having an opening in its bottom, means for discharging and distributing the material through said hopper opening to lay a uniform layer of material on the roadway, a pair of traction members connected to said frame in rear of said hopper and resting on and compressing the roadway already laid, means for applying power to said traction members to propel said frame and means for adjustably varying the elevation of said frame relative to its rear supporting means thereby to vary the pressure of said traction members on said roadway. 55
18. In a road spreader of the character described, a frame, means for supporting the front and rear ends of said frame for movement along the surface to be paved, a hopper arranged in the center of said frame and having an opening in its bottom, means for discharging and distributing the material through said hopper opening to lay a uniform layer of material on the roadway, a pair of traction members connected to said frame in rear of said hopper and resting on and compressing the roadway already laid, means for applying power to said traction members to propel said frame and means for adjustably varying the elevation of said frame relative to its rear supporting means thereby to vary the pressure of said traction members on said roadway. 60
19. In a road spreader of the character described, a carriage, a hopper mounted on said carriage and having a discharge opening in its bottom, a strike-off member arranged adjacent said opening and arranged to smooth out the material discharged through said opening and to determine the thickness of the layer of roadway being laid, an auxiliary frame supporting said 65

- strike-off member, means pivoting said auxiliary frame to said carriage at the front ends thereof, a member supporting the rear end of said auxiliary frame and riding on the surface of the roadway already laid immediately in rear of said strike-off member, and means for adjusting the elevation of the front end of said auxiliary frame to vary the thickness to which the material is spread upon the roadway.
- 5 20. In a road spreader, a carriage, a transverse, flexible strip carried by said carriage, and forming a transverse track, means for varying the longitudinal curvature of said strip in accordance with the crown desired in the roadway, a 10 strike-off member mounted for movement along said flexible strip and following its curvature and means for reciprocating said strike-off member along said flexible strip.
- 15 21. In a road spreader, a carriage having a transverse bar, a flexible track strip arranged under said bar and parallel therewith, means connecting said bar and track strip at spaced intervals and permitting of providing any desired curvature, in a vertical direction, in said 20 track strip, but preventing lengthwise relative movement between said strips, a flexible strike-off strip arranged below said track strip, anti-friction means connecting said track and strike-off strips at spaced intervals and permitting longitudinal reciprocating movement of said strike-off strip but compelling it to follow the curvature of said track strip, and means for reciprocating said strike-off strip.
- 25 22. In a road spreader of the character described, a carriage, a hopper mounted on said carriage and having an elongated discharge opening arranged transverse of the line of movement of said carriage, a strike-off member arranged in rear and parallel with said opening and arranged to smooth off the material being discharged through said opening, a rotary raker arranged in said hopper adjacent said opening, said rotary raker having its axis arranged parallel with said opening and having teeth and means 30 for turning said raker in the direction in which it crowds the material discharged through said opening under said strike-off member.
- 35 23. In a road spreader of the character described, a carriage, a hopper mounted on said carriage and having a discharge opening in its bottom, a strike-off member arranged adjacent said opening and arranged to smooth out the ma- 35
- terial discharged through said opening and to determine the thickness of the layer of roadway being laid, an auxiliary frame supporting said strike-off member, means connecting said auxiliary frame to said carriage and permitting independent vertical movement of said auxiliary frame relative to said carriage, and means for supporting said auxiliary frame on the surface of the roadway already laid immediately in rear of said strike-off member.
- 40 24. In a road spreader of the character described, a carriage, a hopper mounted on said carriage and having a discharge opening in its bottom, a strike-off member arranged adjacent said opening and arranged to smooth off the material discharged through said opening and to determine the thickness of the layer of roadway being laid, an arm carried by said carriage and supporting said strike-off member, means associated with said arm to permit the strike-off member to move vertically independently of said carriage and means for gaging the height of said strike-off member from the surface of the roadway already laid.
- 45 25. In a road spreader of the character described, a frame, traction members supporting the front end of said frame, a traction member supporting the rear end of said frame, a hopper arranged in the center of said frame and having an opening in its bottom, means for discharging and depositing a layer of paving material from said hopper opening to lay a uniform layer of material on the roadway and a strike-off member carried by said frame immediately in advance of said rear traction member for smoothing the said layer to obtain a smooth highway, said front traction members being arranged to travel on the relatively rough surface to be paved and said rear roller running on the paved surface.
- 50 26. In a road spreader of the character described, a frame, steering traction members supporting the front end of said frame, a traction member supporting the rear end of said frame, hopper means carried by said frame intermediate said front and rear traction members and arranged to deposit paving material on the roadway, a strike-off member forming a lower margin of said hopper, and means for oscillating said strike-off member transversely of said roadway so as to assist the spreading of the paving material.

CLYDE G. ABERNATHY.
